CABIN VENTILATOR

Filed Jan. 6, 1930

UNITED STATES PATENT OFFICE

FRANK R. CANNEY, OF SEATTLE, WASHINGTON, ASSIGNOR TO BOEING AIRPLANE COMPANY, OF SEATTLE, WASHINGTON

CABIN VENTILATOR

Application filed January 6, 1930. Serial No. 418,964.

This invention relates to improvements in ventilators and more especially to a ventilator adapted for use in airplanes of the cabin type.

The principal object of the invention is to provide a ventilator of this character which is of light weight, durable and inexpensive construction, and which can be readily mounted in the side walls of the cabin at points within convenient reach of the occupants or passengers.

These and other objects will appear as my invention is more fully hereinafter described in the following specification, illustrated in the accompanying drawings and finally pointed out in the appended claims.

In the drawings:

Figure 1 is a sectional end elevation of a conventional airplane cabin, showing my improved form of ventilator in operative engagement therewith.

Figure 2 is an enlarged front elevation of the ventilator, partly in section.

Figure 3 is a sectional side elevation taken on the line 3—3 of Figure 2.

Figure 4 is a sectional end elevation taken on the line 4—4 of Figure 2.

Figure 5 is an enlarged detail view of an adjustable locking means.

Referring now more particularly to the drawings:

Reference numeral 1 indicates, generally, the cabin of an airplane, having a roof 2, sidewalls 3 and floor 4. The interior of the cabin is provided with the usual seats 5 as shown.

My improved type of ventilator is generally indicated at 6 and is mounted in the walls of the cabin. The main body or frame 7 of the ventilator is of box-like formation and is secured to, and extends through, the side walls of the cabin. Surrounding the frame 7, and extending beyond it, is a grooved frame 8 which is secured to the interior of the cabin wall. Within the grooved frame is slidably mounted a door 9, which is provided with a knob 10 mounted to a spring 11 which is formed with a stud 12 or other suitable projection. An apertured bracket 13 extends transversely of the frame 7 and is secured to

its side walls by means of a bolt 14. The apertures 15 in the bracket are in the path of movement of the spring 11 as it moves with the door 9 in opening or closing so that by pulling outwardly on the knob 10 the stud 12 will become disengaged from the apertured bracket and the door is then free to slide in either direction. Upon releasing the knob, the stud will of course re-engage with the apertures and hold the door in any desired position.

On the opposite or outboard side of the frame 7, a scoop shaped door 16 is hingedly mounted as at 17. A link 18 connects the leading edge of the door 16 with the sliding door 9 so that as the sliding door is opened on the inside of the cabin, the door 16 on the outside will also open. The degree of opening of the outer door can be determined by the amount of opening of the inner door.

The outboard side of the frame 7 is provided with a plurality of baffle plates indicated at 19 which allow free passage of air into the cabin when both doors are open but prevent rain, etc., from entering.

While I have shown a particular form of embodiment of my invention, I am aware that many minor changes therein will readily suggest themselves to others skilled in the art without departing from the spirit and scope of my invention. Having thus described my invention, what I claim as new and desire to protect by Letters Patents is:—

1. In a ventilator of the class described, the combination of a frame member, a door swingably mounted by one edge at one side of said frame member, another door mounted on the opposite side of said frame member in sliding movement in opening away from the hinged edge of the other door, and, means interconnecting both of said doors for imparting swinging motion to one door upon sliding the other of said doors.

2. In a ventilator of the class described, the combination of a frame member, a sliding door on one side of said frame and a swinging door hinged by one edge at the opposite side of said frame, the sliding door moving in opening away from the hinged edge of the swinging door, and a link extending from the

swinging edge of the swinging door back towards its hinge to a connection with the sliding door, to impart swinging motion to the swinging door upon movement of the sliding door.

3. In a ventilator of the class described, the combination of a frame member, a sliding door on one side of said frame and a swinging door on the opposite side of said frame, a link interconnecting both of said doors to impart swinging motion to the swinging door upon movement of the sliding door, a selectively engaging means carried by said frame and said sliding door for arresting the movement of said sliding door, and downwardly inclined baffle plates formed within said frame.

4. In a ventilator of the class described, the combination of a frame member, a sliding door on one side of said frame and a swinging door hinged by one edge at the opposite side of said frame, the sliding door moving in opening away from the hinged edge of the swinging door, and a link extending from the swinging edge of the swinging door back towards its hinge to a connection with the sliding door, to impart swinging motion to the swinging door upon movement of the sliding door, and spaced baffle plates disposed between said doors.

5. In a ventilator of the class described, the combination of a frame member, a sliding door on one side of said frame and a swinging door hinged by one edge at the opposite side of said frame, the sliding door moving in opening away from the hinged edge of the swinging door, and a link extending from the swinging edge of the swinging door back towards its hinge to a connection with the sliding door, to impart swinging motion to the swinging door upon movement of the sliding door, and means for securing the sliding door, and thereby the swinging door, in any one of a plurality of positions.

6. In a ventilator of the class described, the combination of a frame member, a door swingably mounted by one edge at one side of said frame member, another door mounted on the opposite side of said frame member for sliding movement in opening away from the hinged edge of the other door, and means interconnecting both of said doors for imparting swinging motion to one door upon sliding the other of said doors, a bar disposed adjacent the sliding door, and parallel to its direction of movement, a securing member yieldingly supported from the sliding door and engageable with the bar at a plurality of points to hold the doors in selected positions, and a handle operatively connected to the securing member for withdrawing it from engagement with the bar, the yielding support of the securing member insuring its reengagement upon its release.

7. In a ventilator of the class described, the combination of a frame member, a door

swingably mounted by one edge at one side of said frame member, another door mounted on the opposite side of said frame member for sliding movement in opening away from the hinged edge of the other door, and means interconnecting both of said doors for imparting swinging motion to one door upon sliding the other of said doors, a bar disposed transversely of the frame between the doors, and having a plurality of apertures spaced therealong, a handle passing through the sliding door, and having a stud engageable within selected apertures in the bar to secure the doors in selected positions, and spring means supporting the handle and stud and urging the latter into engagement with the bar and its apertures.

In testimony whereof I affix my signature.
FRANK R. CANNEY.
